UNITED STATES PATENT OFFICE.

ORION K. STUART, OF INDIANAPOLIS, INDIANA.

ACETYLENE-GAS PLANT.

1,160,668.

Specification of Letters Patent. Patented Nov. 16, 1915.

Application filed September 30, 1911. Serial No. 652,160.

To all whom it may concern:

Be it known that I, ORION K. STUART, a citizen of the United States, residing at Indianapolis, in the county of Marion and State of Indiana, have invented a new and useful Acetylene-Gas Plant, of which the following is a specification, reference being had to the accompanying drawings and to the letters and figures of reference marked thereon.

This invention relates to low pressure gas plants adapted more especially to generate and supply gas to a relatively small number of consumers, as to one or several adjacent dwellings, stores or work shops, the invention having reference more particularly to means for controlling the generation and storage of acetylene gas in sufficient quantity to supply the requirements of the consumers.

The object of the invention is to provide a complete low pressure acetylene gas plant adapted to be cheaply constructed and to be operated and controlled reliably, and with the minimum degree of danger to the attendant or surrounding buildings; a further object being to improve the apparatus forming the subject of the U. S. Letters Patent No. 749,757, granted January 19, 1904, and provide mechanism for controlling operations of such apparatus automatically so as to maintain a constant supply of gas, a still further object being to combine a plurality of gas generators advantageously with a single gasometer from which to supply the consumers.

Minor objects of the invention will be apparent from the detailed description thereof.

The invention consists in a novel arrangement of acetylene gas generators and a gasometer, and in novel controlling apparatus connected therewith, and also consisting in certain novel parts, and combinations and arrangements of parts, as hereinafter particularly described and claimed.

Referring to the drawings, Figure 1 is a front elevation of an acetylene gas plant constructed substantially in accordance with the invention, portions thereof being broken away to expose internal parts; Figs. 2, 3 and 4, separate detailed views of parts of the apparatus; Fig. 5, a top plan of the apparatus; Fig. 6, a perspective view of the

improved combined weight and guide; Fig. 7, a fragmentary perspective view of one of the filters preferably employed; Fig. 8, a horizontal section of the gasometer on the line A A in Fig. 1; Fig. 9, a vertical central section of one of the generators as on the plane of the line B B in Fig. 5; Fig. 10, a sectional elevation of parts of the generator showing the manner of removing the carbid holder from the gas-holder of the generator or connecting one to the other; Fig. 11, a horizontal section on the line C C in Fig. 9; Fig. 12, a fragmentary section on the line D D in Fig. 9; Fig. 13, a fragmentary elevation of parts shown in the preceding figure; Fig. 14, a fragmentary vertical section approximately on the plane of the line E E in Fig. 5; Fig. 15, a fragmentary sectional elevation on the line F F in Fig. 5; Fig. 16, a fragmentary section on the line G G in Fig. 5; Fig. 17, a section on the line H H in Fig. 16; and Fig. 18, a fragmentary section also on the line G G in Fig. 5.

Similar reference characters throughout the various figures of the drawings indicate corresponding elements or features of construction herein referred to and described.

In a practical embodiment of the invention, preferably two generators are provided and each generator preferably is mounted upon a stand 1 or 1' of suitable height. The generators comprise essentially two tanks or water-holding vessels 2 and 2' and two gas bells or holders 3 and 3', respectively, each vessel including a bottom 4, the top of the vessel being open, and the gas-holder including a top 5. The gas-holder is inserted into the vessel and is removable therefrom, and it has an open lower end adapted to be water-sealed in the vessel, as will be understood. A stand 6 preferably is arranged between the stands 1 and 1' and it supports a tank 7 in which a gasometer bell 8 is guided movably, the latter including a top 8' which is opposed to the bottom 7' of the tank, and as will be understood it is designed that the bell, the lower end of which is open, be water-sealed in the tank as is customary.

Each gas-holder has a suitable carbide holder connected removably to the inner side thereof, and each carbide holder comprises a side wall 9 and also a bottom 10 having perforations 11 therein, the bottom having

a central aperture in which is secured a tube 12 provided with a projecting flaring lower end 13. Each carbid holder is provided with a suitable number of lugs for supporting it, each lug preferably comprising two horizontal plates 14 and 14' provided with ears 15 and 15' which are secured to the wall 9, the plates having guide-plates 16 and 16' thereon which are connected to a tie-plate 17. The inner side of the gas-holder is provided with a corresponding number of socket-like brackets somewhat similar to the lugs in contour, each comprising two horizontal plates 18 and 18' provided with ears 19 and 19' which are secured to the wall of the gas-holder, there being two guide-plates 20 and 20' extending downward from the plates 18 and 18' and connected to a horizontal plate 21, the design being such that the plate 17 may slide in contact with the top of either plate 18 and 18' until the plates 16 and 16' may pass down between the plates 20 and 20', as a dowel entering a socket. Each carbid holder has a basket arranged removably therein which comprises a side wall 22 having perforations 23 therein, and also a bottom 24 having perforations 25 therein, a tube 26 being connected to the bottom at a suitable aperture therein, the tube being slightly greater in diameter than the tube 12 and normally extending around it. The basket is provided with a bail 27 and also a suitable number of annular plates 28 having perforations 29 therein to be placed between layers of carbid in the basket, for the purpose of preventing the whole bulk of carbid from becoming packed too densely for proper generation of the gas.

Two platforms are provided and arranged adjacently to the generators, and each comprises an annular table 30 or 30' having each a suitable opening 31 therein to receive the flaring end 13 of the tube 12, the tables being provided with supporting legs 32 of suitable length to support one of the carbid holders and permit the gas-holder to descend so as to disconnect the brackets from the lugs, so that the gas-holder may be rotated slightly and then lifted away from the carbid-holder to permit the latter to be recharged with carbid.

Each water-holding vessel 2 and 2' is provided with a central outlet pipe 33 which is secured to and extends through the bottom of the vessel and upward approximately to the upper end thereof, an elbow 33' preferably being connected to the lower end of the pipe below the bottom of the vessel. Each vessel is provided with a drain-pipe 34 provided with a stop-cock 35. The top 5 of each gas-holder has a collar 36 secured thereon which is provided with an outwardly extending flange 37 in which are a suitable number of holes 38. The top 5 is conical and a vent-cock 39 is connected to the apex

of the top for permitting air to escape after recharging the generator with carbid. A bail 40 is connected to the collar 36 whereby to lift and carry the gas holder and the carbid therein, it being understood that any suitable power lift may be employed for the purpose. The upper end of each vessel 2 and 2' is provided with an outwardly tending flange 41 on each of which a suitable number of brackets 42 are mounted, two sheaves 43 and 44 being mounted in each bracket, one sheave being approximately above the other.

An annular combined weight and guide 45 is arranged in each water-holding vessel 80 exteriorly to the gas-holder and has a suitable number of cables 46 connected thereto that extend upward in contact with the sheaves 44 and thence around the sheaves 43, each cable having a hook 47 on its upper end which is inserted removably in one of the holes 38. In some cases supplemental weights 48 are placed on the cables. Each gas holder 3 and 3' is provided on the exterior thereof with an indicator plate 49 having divisional marks 50 thereon, preferably one inch apart and numerals 51 indicating inches from the upper end of the plate downward. Each combined weight and guide consists preferably of a ring of metal 95 having considerably greater height than width in cross-section and provided with guide projections or adjustable guide screws 52 and 53 adapted to be adjusted, so as to be nearly in contact with the opposing walls 100 of the vessel 2 and gas-holder 3, there being ample space allowed for free circulation of the water past the ring. While the lower portion of the gas-holder is guided by the annular weight and guide, the upper end is 105 guided by means of the cables which are of equal length. The tube 12 is sufficiently large to pass freely over the outlet pipe 33.

The tank 7 has a suitable number of upright guide-bars 54, 54', on the wall thereof 110 and they extend upward to a suitable height beyond the top of the tank and are connected to a stay-ring 55, the exterior of the gasometer 8 being provided with a suitable number of grooved guide-rollers 56 and 56' 115 that are in contact with the guide-bars. The top 8' is provided with a vent-cock 57. Two inlet pipes 58 and 58' and also an outlet pipe 59 extend through and are secured to the bottom 7' of the tank and extend upward 120 nearly to the plane of the top of the tank, each pipe preferably having a hooded filter 60 extending over its upper end to filter the gas and prevent possible condensation on the top 8' from dropping into the pipes. The 125 lower end of each pipe is provided with a drain-cock 61 for draining condensation from the pipes or making tests as to the presence of moisture in the connecting pipes. Preferably the tank is provided with a 130

drain-pipe 62 provided with a stop-cock 63. The exterior of the bell 8 has an indicator plate 49 thereon, as above described, so that the volume of gas therein may be ascertained at any time.

Two gas-pipes 64 and 64' are connected to the elbow 33' of the outlet pipes 33 of the two generators and have stop-cocks 65 and 65' connected thereto, respectively, to which are connected pipe sections 66 and 66' having pipe-tees 67 and 67' connected thereto, to the lower portions of which drain-cocks 68 and 68' are connected, the tees being suitably connected with pipe unions 69 and 69' with which suitable gas purifiers 70 and 70' are connected in vertical arrangement, the upper ends of the purifiers being suitably connected with unions 71 and 71' with which valve-bodies 72 and 72' are connected, respectively, the valve-bodies being further described hereinafter. Pipe-sections 73 and 73' are connected to the valve-bodies and have horizontal sections 74 and 74' connected therewith, suitable vertical pipe sections 75 and 75' extending downward from the horizontal sections and having stop-valves 76 and 76' connected thereto, respectively, pipe sections 77 and 77' being connected with the valves and having horizontal sections 78 and 78' connected therewith, the latter sections being connected with the pipes 58 and 58', respectively. A pipe 79 is connected with the outlet-pipe 59 and is provided with a regulating valve 80 with which is connected a service pipe 79'.

Each valve-body 72 and 72', is substantially cylindrical and has two valve-seats 81 and 81' extending inwardly a short distance from different portions of the wall thereof in parallel planes, and a shaft 82 is mounted rotatably in the wall of the body between the two planes and has a butterfly type intercepting valve 83 secured thereto which is adapted to rest against the seats 81 and 81' for closing the passage through the valve-body or to be moved rotatively from the valve-seats as indicated by broken lines in Fig. 18 to open the passage. Each shaft 82 has a clamp-head 84 thereon and secured adjustably by means of a set screw 85 which secures also a spring-clamp 86 which adjustably secures an operating lever or arm to the shaft, there being two levers or arms 87 and 87' connected to the shafts of the two valves respectively, each lever being connected between its ends to the shaft, and preferably the upper side of each lever has a suitable number of notches 88 therein for retaining a weight 89 in position when hung on the lever near one end portion thereof, the opposite end portion of each lever having an aperture 90 therein. Two push rods 91 and 91' are each connected suitably to the gasometer bell 8, preferably by means of a connecting arm 91'', the push-rods being vertical and

extending downward near the outer side of the tank 7 and through the apertured ends of the levers 87 and 87', respectively, each push rod having a button 92 secured adjustably thereto by means of a set screw 93 so as to be moved into contact with the top of the lever to operate it. Two cords or chains 94 and 94' are connected to the levers 87 and 87' at the opposite ends thereof from the apertured ends, and the cords or chains are suitably connected to the gas-holders 3 and 3', respectively, preferably by means of arms 95 and 95'. Each lever 87 and 87' has a projection 96 thereon near the portion to which the cord or chain is connected, and is provided also with a roller 97 and a yoke 98 to which a spring finger 99 is secured and adapted to spring over toward the projection 96, for a purpose which will further appear. It will be understood that a roller 97 is preferable in order to lessen friction, but if desired may be incapable of rotation.

A suitable foundation 100 is provided that has a suitable number of bolt-holes 101 therein, and a pivot-stand 102 is secured suitably on the top of the foundation by means of bolts 101', and it has a pivot 103 thereon on which is mounted a relatively long controlling lever 104 provided with a suitable number of pivot holes 105 nearer to one end than the opposite end thereof, so that the lever is pivoted at either one of the pivot holes desired and the stand may be adjusted on its foundation accordingly without shifting the lever from the position in which it is required to operate.

It will be understood that the tendency of the longer end of the lever is to descend by gravitation and hold up the shorter end thereof. Two trip rods 106 and 106' are pivotally connected to opposite ends of the lever 104 and have arms 107 and 107' secured thereto respectively by set-screws 108, so as to be adjustable, and push-bars 109 and 109' are connected to the arms, respectively, and extend upwardly, each through the yoke 98 in contact with the roller 97 and spring-finger 99, each push-bar having a ratchet-tooth 110 thereon adapted to move downward or upward over the roller, and when moved upward, to engage the projection 96 when the lever 87 or 87' is at an inclined angle, and to be pushed away from the projection by means of the roller when the lever rises toward a horizontal position to open the valve 83. Each trip-rod has an eye 111 in its upper end and a clamping collar 112 that is adjustable on the upper portion of the rod. The trip-rods comprise also extension stems 113 and 113' which are adjustably connected to the main parts 106 and 106' by means of the clamps 112, and they extend through the flanges 41 of the vessels 2 and 2', respectively, the upper ends of the stems having each a crook 114 thereon from

which return branches 115 and 115' extend downward adjacent the wall of the vessel and have feet 116 and 116' thereon, respectively, that extend inward so as to be engaged by the lower ends of the gas holders 3 and 3' when they descend thereto.

In practical use, the carbide holders are placed upon the platforms provided therefor and the baskets having been supplied 10 with lump carbide are placed in the holders, and then the gas holders are lowered over the platforms so as to inclose the carbide holders, somewhat as shown in Fig. 10, and then the gas holders are rotated until the 15 socketed brackets may receive the lugs of the carbide holders, and then the gas holders are elevated and carry the carbide-holders therein to the required position above the water holding vessels into which they are lowered, 20 and then the hooks 47 are properly connected to the flanges 37. The vent-cocks 39 are opened if necessary to permit the carbide to descend into the water which it will be understood may be placed in the vessels 25 either before or after charging the carbide holders, and it will be understood that the carbide holders are charged more conveniently one at a time. The carbide becoming moistened results in generation of gas which 30 rises in the gas-holder and forces it upward, and gradually the production of the gas ceases while the carbide is elevated above the water, and the gas holder will remain elevated while communication is closed between 35 it and the gasometer, but if sufficient gas is generated to elevate the gas-holder until the cord 94 or 94' pulls up the lever 87 or 87' and opens the valve 83, the gas will flow into the gasometer and permit the gas-holder to 40 again descend so as to lower the carbide to the water, the intercepting valve 83 again closing or not as may be previously arranged, depending upon whether or not it is overbalanced. Generation of gas again 45 occurs and the gas holder is again elevated and opens the intercepting valve. But a sufficient volume of gas may not be generated to take the slack out of the cord, so that the intercepting valves may remain closed, 50 and then if the supply in the gasometer becomes nearly exhausted the buttons 92 are moved down upon the levers and move them or one of the levers, depending upon the relative adjustments, so as to open the intercepting valve and permit the gas to flow 55 from the gas-holder into the gasometer, so that the carbide may again descend to the water and start generation of the gas. When no more gas can be produced from the carbide the gas holder descends until it pushes down the foot 116 or 116' and operates the lever 104 so as to open the intercepting valve of the other charged generator and thus 60 puts it into operation, at the same time permitting its own intercepting valve to be

closed by the weight of its lever. Thus while one generator is in operation the other one may be conveniently recharged and held in readiness to be automatically put into operation when the working generator has become exhausted.

The results of operation not specifically pointed out will be readily understood by reference to the description of the details of construction and functions of the several 75 parts.

Having thus described the invention, what is claimed as new, is—

1. An acetylene gas plant including a gas-generator, a gasometer comprising a movable bell, a conduit connecting the gasometer and the gas-generator and provided with a balanced intercepting valve having an operating lever that is connected to the valve, the lever being weighted to automatically 80 close the valve, a flexible device connected with the operating lever and actuated by the gas-generator to move the lever and open the valve following the generation of gas, the flexible device permitting the lever to be 85 independently moved, an auxiliary gas-generator, a movably supported connecting appliance adapted to automatically engage and move the operating lever when moved in one direction to open the valve, the appliance being adapted to be automatically actuated by either the gas-generator or the auxiliary gas-generator on exhaustion of the 90 gas generated therein, and a device carried by the gasometer bell into engagement with 95 the operating lever to open the valve on exhaustion of the gas in the bell.

2. An acetylene gas plant including a gas-generator with a movable bell, a gasometer, a conduit for the passage of gas connecting 100 the gas-generator and the gasometer and provided with an intercepting valve having a weighted operating lever for automatically closing the valve, a trip-rod vertically guided adjacent to the gas-generator and adapted 105 to be engaged and moved downward by the generator bell, a push-bar connected to and carried by the trip-rod and guided adjacent to the operating lever, the trip-rod permitting 110 free movement of the lever, a pivotally supported controlling lever connected to the trip-rod for moving the latter upward, means enabling the push-bar to engage and move the operating lever to open the valve on upward movement of the push-bar and permitting downward movement of the push-bar free of the lever, and a device connected 115 to the operating lever and forming a connection with the generator bell for moving the lever to open the valve.

3. An acetylene gas plant including a gas-generator comprising a movable holder, a gasometer tank, a bell movable in the tank, a push-rod fixedly secured to the bell, a contact device fixed on the push-rod, a con- 120

duit extending from the gas-holder into the bell and provided with an intercepting valve for control of the passage of gas from the gas-generator to the bell, an operating lever connected between its ends with the valve for control of the valve, one end portion of the lever extending approximately to the push-rod to be engaged on its top by the contact device when the bell is moving downward to move the lever for opening the valve, the opposite end portion of the lever being overbalanced and when unrestrained acting as a weight to close the valve, and a flexible cable connected with the holder and one end portion of the lever for enabling the gas-generator holder following the generation of gas to move the lever to open the valve.

4. An acetylene gas plant including a gas-generator comprising a water-holding vessel and a gas-holder movable in the vessel, a tank, a gasometer bell movable in the tank and having a push-rod fixedly secured thereto, a contact device fixed on the push-rod, a conduit extending from the interior of the gas-holder to the interior of the bell and provided with an intercepting valve, an operating lever connected between its ends with the valve, one end of the lever extending approximately to the push-rod to be engaged on its top by the contact device to open the valve, the opposite end of the lever being weighted to close the valve, and a cable connected with the gas-holder and the weighted end portion of the operating lever.

5. An acetylene gas plant including a gas-generator comprising a water-holding vessel and a gas holder movable in the vessel, a tank, a gasometer bell movable in the tank and having a push-rod fixedly secured thereto, a button secured adjustably to the push-rod, a conduit extending from the interior of the gas holder to the interior of the bell for the passage of gas and provided with an intercepting valve, the valve having a rotatable operating shaft, a lever secured between its ends to the shaft and having an aperture in one end portion thereof through which the push-rod extends, the end being engaged by the button to move the lever for opening the valve, and a cable connected to the opposite end portion of the lever and also to the gas holder for independently opening the valve.

6. An acetylene gas plant including two gas-generators, a gasometer, a conduit connected with one of the gas-generators and the gasometer and provided with an intercepting valve, a conduit connected with the other one of the gas-generators and the gasometer and provided with an intercepting valve, a lever pivotally supported between its ends, trip devices connected with one end of the lever and adapted for opening one of the valves, trip devices connected

with the opposite end of the lever and adapted for opening the other one of the valves, means enabling one of the gas-generators to move one end of the lever, and means enabling the other one of the gas-generators to move the opposite end of the levers.

7. An acetylene gas plant including two water-holding vessels, two gas holders movable in the vessels, one in each, a tank, a gasometer bell movable in the tank, a pipe extending from the interior of one of the gas holders to the interior of the bell and provided with an intercepting valve having an operating lever, a pipe extending from the interior of the other one of the gas holders to the interior of the bell and provided with an intercepting valve having an operating lever, a trip-rod guided movably on one of the vessels and having an extension adapted to be moved by the gas holder in the vessel, a trip-rod guided movably on the other one of the vessels and having an extension adapted to be moved by the gas holder in the vessel, two push-bars connected respectively with the two trip- rods and extending adjacent to the two operating levers respectively, means enabling the push-bars to move the levers on movement in one direction only, and a lever pivotally supported between its ends and connected at its two opposite ends to the two trip- rods respectively.

8. In an acetylene gas plant, the combination of a water-holding vessel, a gas holder movable in the vessel, a tank, a gasometer bell movable in the tank, an annular carbide holder supported on the interior of the gas holder, a pipe extending from the interior of the gas holder through the carbide holder and the bottom of the vessel, an intercepting valve connected with the pipe, an operating lever connected between its ends with the valve, a pipe extending from the valve to the interior of the bell, a cable connected to the gas holder and also to the operating lever to move the latter in one direction for opening the valve, a device connected to the bell and adapted to move the lever in said one direction, and a weight adjustably mounted on the lever to move it in the opposite direction for closing the valve.

9. In an acetylene gas plant, the combination of a water-holding vessel, a gas holder movable in the vessel, a tank, a gasometer bell movable in the tank, a carbide holder mounted in the gas holder, a pipe extending from the interior of the gas holder through the bottom of the vessel, a valve body having a passage connected with the pipe, a shaft mounted rotatably in the body, a valve on the shaft for closing the passage, a pipe connected with the valve body and extending into the bell, an operating lever secured adjustably between its ends to the shaft

and having an aperture in one end portion thereof, a push-rod secured to the bell and extending through the aperture, a contact device secured to the push-rod for moving the lever, and a cable connected to the opposite end portion of the lever and also to the gas holder.

10. In an acetylene gas plant, the combination of two gas-generators, a gasometer comprising a tank and a bell, two conduits connected respectively with the gas-generators and also with the bell, two intercepting valves connected respectively with the two conduits and having each an operating lever for closing the valves, separate means enabling the bell to move the levers separately to open the valves, a reversing lever pivotally supported between its ends and provided on opposite ends thereof with separate means for separately moving the two operating levers respectively to open the valves, and separate means enabling the two

gas-generators respectively to separately move the reversing lever.

11. In an acetylene gas plant, the combination of two gas-generators, a gasometer, two conduits connected respectively with the two gas-generators and also with the gasometer, valve means for closing the two conduits, separate operating and controlling means operatively connected together and with the two gas-generators respectively for enabling either one of the gas-generators when exhausted to actuate the operating and controlling means for putting the remaining one of the gas-generators into operation and opening the valve means between it and the gasometer.

In testimony whereof, I affix my signature in presence of two witnesses.

ORION K. STUART.
